UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, AND DETROIT, MICHIGAN, A CORPORATION OF NEW JERSEY.

TOP CONSTRUCTION.

Application filed July 9, 1924. Serial No. 725,062.

This invention relates to tops for motor vehicles and the like and particularly to permanent tops which are used on automobile bodies of the open type.

5 One of the objects of this invention is to provide a top of the class described of novel and improved construction, the main portion of the frame of which may be constructed of metal stampings to render it strong and durable and yet of less weight than metal tops previously in use.

Another object of the present invention is to provide a permanent top for an automobile in which the various top supporting members are secured to the top so that the completed structure forms a single unit attachable to the automobile as such.

20 Another object is to provide such a top in which the metal side members of the frame constitute the top side quarters and which may be provided with means for supporting roller curtains.

Another object is to provide top supporting members with guides or grooves to receive the front and rear edges of the front and rear curtains respectively when the curtains are in extended or lowered position and thus serve as means to prevent the ingress of the elements of the weather to the 30 interior of the vehicle.

A further object is to provide a removable cover or shield for enclosing that part of the interior of the top quarter which carries the curtain rollers, the lower edge of 35 the shield acting as a guide for the curtains when the same are being raised or lowered.

A still further object is to provide a body construction having the beauty of design and conveniences afforded in "closed" bodies 40 but at less cost and of much less weight.

The above being among the objects of the present invention the same consists of certain features of construction and combination of parts to be hereinafter described 45 with reference to the accompanying drawings, and then claimed, having the above and other objects in view.

In the accompanying drawings which illustrate a suitable embodiment of the present invention, and in which like numerals 50 refer to like parts throughout the several views.

Figure 1 is a perspective view of the complete top as it appears upon an automobile.

Figure 2 is a perspective view of the complete top frame before the covering, lining, and other finishing parts are secured thereto.

Figure 3 is a fragmentary sectional perspective view of a portion of the top, taken perpendicularly to the length of the top between the second and third cross ribs, the curtains being removed to more clearly show the curtain supporting brackets and the mid-support for the curtain shield.

Figure 4 is a fragmentary sectional perspective view of a portion of the top taken in a plane parallel to that of the section shown in Figure 3, but slightly to the rear of the shield mid-support, the curtains and curtain shield being shown in place, and the 70 top cross ribs not being shown to more clearly show the other features.

Figure 5 is a perspective view of the inner side of the completed top, the curtain shield being shown displaced from normal position 75 to better illustrate the invention.

Figure 6 is a perspective view of one of the rear quarter panels.

Figure 7 is a fragmentary perspective sectional view illustrating the manner in which 80 the rear quarter panels are secured to the top proper.

Figure 8 is a fragmentary perspective sectional view illustrating the manner in which the rear quarter panels are secured to the 85 body.

Figure 9 is a perspective sectional view of a portion of one of the side quarters showing the means used for attaching the longitudinally extending shield attaching strip 90 thereto.

Figure 10 is a fragmentary perspective view of one of the top front supports and top front cross member, showing the method 95 of securing the same together.

Figure 11 is a fragmentary perspective view of one of the top front supports and co-operating curtain.

Figure 12 is a fragmentary sectional view 100 of one of the top front supports and co-operating curtain, taken on the line 12-12 of Figure 11 and illustrating means employed to prevent the curtain from withdrawing from the groove in the support.

Figure 13 is a fragmentary side view of a portion of one of the curtains, showing the clip secured thereto which engages the grooves in the supports and thereby prevents the curtains from withdrawing from the same.

Figure 14 is a side view of one of the top rear supports.

Figure 15 is a section of the top rear support taken on the line 15—15 of Figure 14.

Figure 16 is a front edge view of the upper portion of the top rear support shown in Figure 14.

Figure 17 is a section of the top rear support taken on the line 17—17 of Figure 14.

Figure 18 is a fragmentary perspective view of that part of one of the curtains which embodies the grommet for holding the curtain in unrolled position, to the door of the vehicle body.

Figure 19 is a fragmentary perspective view of a part of the vehicle body door showing the catch for engaging the grommet shown in Figure 18.

Figure 20 is a perspective sectional view illustrating a fragment of one of the top cross ribs.

Figure 21 is a fragmentary view looking from beneath the top and showing the method of attaching the side quarters to the front cross member.

The frame of the top is composed mainly of metal stampings, as best shown in Figure 2, and consists of side members or quarters 30, rear member or quarter 31, front cross member 32 and a plurality of cross ribs 33. The side members 30 are preferably formed from sheet metal and are constructed to serve as the top side quarters, that is to say, they curve upwardly and inwardly from their lower edge to form with the cross ribs the frame for the flat upper portion of the top and they extend from the front cross member 32 rearwardly to the rear quarter 31, conforming to the shape of that part of the finished top throughout. The rear quarter curves upwardly and inwardly from the bottom edge to the flat portion of the top in identically the same manner as the side quarters, and its ends are curved over to conform to the adjacent edge of the side quarters and are suitably secured thereto by screws, welding or other means. The front cross member is preferably formed of wood to more easily attach the windshield 81 and rain shield 82 thereto. As shown particularly in Figure 9 the lower edge of the side quarters 30 and rear quarter 31 are turned inwardly to form a horizontally extending flange 83 for a purpose to be described hereafter, and the upper edge is bent downwardly and then inwardly to form an extending flange 84 below the plane of the top. Extending between the side quarters I have shown six approximately equally spaced me-

tallic cross ribs 33 having an inverted U shaped section with the open end of the U flanged outwardly as shown in Figure 20. The flanged portion is secured by riveting or welding to the horizontally extending flange 84 at the upper edge of the quarters 30 and the height of the ribs 33 is such that their upper face is flush with the upper face of the quarters 30. Alternate ribs 33 are shown as provided with a wooden strip 34 lying against one side of the U and its corresponding flanged end to serve as tacking strips for the top covering. While six cross ribs and wooden strips secured to the alternate ribs have been illustrated, any suitable number of ribs and any arrangement of wooden strips can be provided as needed to accomplish the desired result.

The side quarters are each provided with a forwardly extending projection 35 which is set into and secured to the front cross member 32 as shown in Figure 2, and a short angle bar 36 is bolted to the rear face of the front cross member 32 and is bent around and secured to the lower inwardly flanged edge 83 of the side quarter 30 as shown in Figure 21 to rigidly secure the front cross member 32 to the side quarters 30. A similar angle 37 is bent to conform to the shape of the top adjacent the meeting edges of the side quarters 30 and rear quarter 31 and is secured to the lower inwardly extending flange 83 of these members to better secure them together. (See Figure 7.)

Welded, riveted or otherwise secured to the inner curved surface of the side quarters 30 are brackets 38 and 39 which are provided to support the rollers 40 in which the roller curtains 41 are mounted. Brackets for two of such curtains 41 are provided for each side, the rear curtains being arranged above the front curtains and the forward bracket for the rear curtain being positioned forward of the rear bracket for the front curtain so that the rear edge of the front curtain will overlap the front edge of the rear curtain and will effectually prevent the entrance of rain or dust therethrough.

Secured to the underside of the side quarters 30 adjacent the inner flanged edges 84 thereof by the brackets 42 is a longitudinally extending strip 43 (see Figure 4) which serves as a tacking strip for the edges of the inner top covering 44 and also as a support for the shield 45 which is secured thereto by screws or other suitable means and which serves as a finishing strip to enclose the curtains 41 in the quarters 30. The lower edge of the shield 45 extends downwardly and inwardly to lie in a plane adjacent the inwardly turned flange 83 at the bottom of the side quarters 30 and serves to guide the curtains and hold their upper edges in correct vertical position when the curtains are in lowered position.

A support or brace 46 to which the shield 45 is removably mounted is secured to the quarter 30 substantially midway of its ends by welding, riveting or other suitable means. 5 The support 46 can be made of any of the well known materials and I have shown the same formed of strip metal to provide a portion secured to the upper portion of the quarter 30, and a curved depending portion 10 to which the shield 45 may be secured, and an upwardly and outwardly curved portion formed to extend over and clear the curtain 41, and a depending flange adapted to be secured adjacent the lower edge of the 15 quarter 30.

The top previously described can be completely assembled if desired before being mounted on the vehicle and can be supported thereon in any convenient manner by suitable supporting means and I have found that the means illustrated and about to be described affords such a supporting means which is very substantial and attractive in appearance. 20

25 I have shown the top supported on the body of the automobile by the front supports 47 and rear supports 48, the rear supports 48 being placed a substantial distance in front of the rear of the top and therefore 30 carrying a major portion of the weight of the entire top. The front supports 47 are positioned at the extreme front of the top and carry a relatively small portion of the weight of the top but act to steady the front 35 end thereof and to guide the curtains 41 as will be explained hereafter. The front supports 47 may be secured to the body of the automobile by any of the well known methods used in securing the conventional 40 windshield posts to the body, and at their upper ends are provided with an offset flange 49 which is secured to the angle member 36, which acts to tie the front cross member 32 and side quarters 30 together, by 45 means of bolts 50 and nuts 51.

As clearly shown in Figures 10, 11 and 12 the support 47 is formed to provide a vertically extending slot or groove 52 in its rear face which is adapted to receive and guide the front edge of the front curtain 41, the inner or blind end of the groove being enlarged to receive the buttons 53 which are secured to the front edge of the front curtains 41 at spaced intervals for preventing 50 the curtains 41 from pulling out of the groove 52.

The front edge of the top rear support 48 is curved in shape to blend into the lines of the top and body and is provided with a 55 groove 54 (see Figure 15) opening out on that face and the groove is adapted to receive the rear edge of the rear curtain 41 for holding and guiding the same. As shown in section in Figures 15 and 17, this member 60 is made up of a plurality of stampings

welded, brazed or otherwise suitably secured together to form a section of very great strength and rigidity and at the same time to provide the groove 54 which extends through its length and which opens up into an enlarged pocket 69 at the rear face thereof to receive the buttons 53 which are fastened to the rear edge of the rear curtain 41 in the same manner and for the same purpose as those described for use at the front 70 edge of the front curtain. The rear support 48 is further formed adjacent the front edge on the outside face thereof with a pocket extending the full length of that edge for receiving and holding the tacking strip 55 for 75 the top covering 56. The upper end of the rear support 48 is secured to the side quarter 30 by means of bolts or screws 57 (see Figure 9) which pass through the short angle member 58 overlying the inwardly turned lower flanged edge 83 of the quarter 30 and thread into the support 48 thus securely holding the one to the other. A flat metal guide 59 projecting above and inwardly from the upper end of the support 48 80 serves to guide the edge of the curtain 41 into the slot 54. Bolts 60 securely anchored in the lower end of the support 48 pass through holes in the top rail 65 of the automobile body 61 and receive nuts thereon 85 which securely hold the support 48 to the body 61. (See Figure 5.)

Suitably secured to the lower face of the flanged lower edge 83 of the quarters 30 and 31 other than at the points where the supports 47 and 48 are secured thereto is a tacking strip 62 for tacking the sides of the top covering 56 to the top. The curved face of the top rear quarter 31 is provided with a 100 row of slots or holes 63 under which a tacking strip, not shown, is secured to provide a means for securing the meeting edges of the top covering 56 and the covering for the back of the top and rear panels 64 which extend around the rear curved corners of the 105 top between the body 61 and side and rear quarters 30 and 31. The rear panels 64 are provided with an inwardly flanged upper edge which lies against the tacking strip 62 and through which suitable screws 80 pass 110 and thread into the angle 37 previously described. The lower edge of the panels 64 abuts against a bead 66 formed in the automobile body 61 adjacent the upper edge thereof and is secured in place by screws 67. 115 Although the purpose of the rear panels 64 is to form a smooth and neat appearing back to the top, it will be noted that it also acts to considerably stiffen the top and anchor it against movement. 120

The top frame is constructed with the central portion open and bridged only by the ribs 33 to eliminate the drumming usually associated with tops in which the metal extends completely over the same. If a 125

dome lamp is desired a block such as 68 may be positioned between any of the adjacent ribs 33 and be secured thereto as shown in Figure 2. To support the top covering 56 over the open space between the ribs 33 conventional tape or fabric strips 70 are secured longitudinally of the top to the tacking strips 34 for that purpose. The inner top covering 44 is secured in place in the conventional manner to the tacking strips 34 and its edges are secured to the longitudinally extending strips 43 as previously described. The shield 45 being covered with lining material serves to finish the sides of the interior of the top 61.

If desired side windows 71 may be permanently supported by the top covering 56 between the top rear supports 48 and their adjacent rear quarter panels 64 and a rear window 72 may be supported by the same top covering 56 between the rear quarter panels 64.

As previously described, I prefer to use curtains 41 of the roller type and have shown the same provided with celluloid or other flexible transparent windows 73 which are capable of being rolled up with the curtains around the roller 40. The lower front edge of the front curtains and the lower rear edge of the rear curtain are preferably notched or cut away (see Figure 1) so that when the curtains are pulled down to their extreme position the lower edge of the curtains will overlap the side of the automobile body to provide a secure joint therebetween. Each curtain is provided adjacent the lower edge and in the center thereof with a grommet 74 which is adapted to engage the catch 75 secured adjacent the upper edge of the body 61 in a position to engage the same and prevent any tendency of the curtain to flap. Immediately above the grommet 74 an opening 76 is provided in the curtains 41 to allow an occupant of the vehicle to insert his hand therethrough and engage the grommet 74 with the catch 75. A flap 77 sewed or otherwise secured to the curtains 41 above the opening 76 normally closes the same. A small angular piece of metal 78 secured to the lower edge of the flap 77 with one leg of the angle projecting therefrom may be provided to engage the tacking strip 62 when the curtains are raised and prevent the curtains from rolling up to a point which would render them inaccessible to the hand of a person wishing to grasp them to pull them down. To further facilitate grasping of the curtains 41 when in rolled up position the shield 45 may be provided with a notch adjacent the center of each curtain to expose the edge of the curtain at that point. (See Figure 5.)

As a means for further preventing flapping of the curtains an upwardly extending finger 79 may be secured to the side of the body 61

to protect the overlapping edges of the curtains. The finger 79 is preferably spaced from the side of the body a distance equal to the thickness of the edges of the two curtains and between which and the body the curtains 70 are adapted to lie when in fully pulled down position.

Although I have illustrated a top construction wherein two curtains are mounted for use when desired, it will readily be seen by those skilled in the art that the construction can be modified to include the use of a greater number of curtains or equally good results can be obtained by the use of one curtain. This latter construction would be very desirable in the use of tops of the permanent type when used on automobiles of the roadster type. While I have illustrated one form of mounting for the curtains, it will also be understood that I do not wish to limit my invention to the specific means illustrated as I have found that various means of supporting the curtains may be employed which will so position the same that the meeting edges of the curtains will overlap to provide a suitable closure for the occupants of the vehicle. It will also be seen that in the use of this type of top for long vehicles such as busses that it may be desirable to provide supporting members for the top intermediate the front and rear supports and that such supporting members can be provided with grooves or ways to receive the edges of the curtains adjacent thereto in the same manner as described for use in the construction illustrated. Likewise other changes can be made in the specific embodiment of the invention described without departing from the spirit and substance of the broad invention, the scope of which is commensurate with the appended claims.

What I claim is:—

1. The combination with an automobile of the open type of a permanent top therefor, the frame of said top comprising continuous coved sheet metal side and rear quarters permanently secured together, a front cross member secured to the forward ends of the side quarters, the lower edge of said side and rear quarters being bent inwardly to form a horizontally extending flange, members conforming in shape to the top secured to said flange adjacent the meeting edges of the said top and rear quarters, angle members connecting said flange and said front cross member, a vertically extending support projecting up from said body and being secured to the angle member connecting said side quarters and said front cross member, and vertically extending supports projecting up from said body at a substantial distance forward of the rear edge of said top secured to said horizontally extending flange.

2. The combination with an automobile of the open type, of a permanent top therefor,

said top having a frame comprised of continuous coved sheet metal side and rear quarters permanently secured together and a front cross member rigidly secured across overlapped relation, and members for supporting said top on said automobile, said members being provided with a groove in 10 one face thereof for guiding said curtains.

5 the front ends of said side members, brackets secured to the inner surface of said side quarters for supporting roller curtains in

Signed by me at Detroit, Michigan,
U. S. A., this 2nd day of July, 1924.

JOSEPH H. BOURGON.
